UNITED STATES PATENT OFFICE.

JOHN L. BUEHL, OF CHICAGO, ILLINOIS.

COLLAPSIBLE OR INTERCHANGEABLE CASE.

1,141,865.

Specification of Letters Patent.

Patented June 1, 1915.

Application filed March 14, 1913. Serial No. 754,229.

To all whom it may concern:

Be it known that I, JOHN L. BUEHL, a citizen of the United States, residing at Chicago, in the county of Cook and State 5 of Illinois, have invented certain new and useful Improvements in Collapsible or Interchangeable Cases, of which the following is a description.

My invention belongs to that general class 10 of devices known as interchangeable cases or boxes, and relates particularly to a case of the kind described, suitable for containing bottles, as for example, beer bottles, but its use, however, is not limited to that alone, 15 as the boxes may be employed wherever found applicable.

The invention has among its objects the production of a case of the kind described that is simple, compact, durable, of light 20 weight, convenient, efficient and satisfactory; that may be manufactured at comparatively small cost; that is made up of interchangeable parts, and that will occupy small space during storage or shipping, 25 when knocked down. In case of breakage of any part of the box or case, the same being interchangeable, the broken parts may be easily and quickly replaced or renewed at small cost. The old cases may be 30 repaired with new parts, or those parts of broken cases that are in good condition may be used to replace the broken parts of other cases.

To this end my invention consists in the 35 novel construction, arrangement and combination of parts herein shown and described, and more particularly pointed out in the claims.

In the drawings, wherein like reference 40 characters indicate like or corresponding parts, Figure 1 is a side elevation of my improved case. Fig. 2 is a top plan-view of the same provided with a cover. Fig. 3 is an enlarged view in elevation of a portion 45 of the corner. Fig. 4 is a portion of Fig. 2 enlarged, showing one of the hinges. Fig. 5 is substantially a sectional view taken on line 5, 5 of Fig. 2. Fig. 6 is a top plan view of the same. Fig. 7 is substantially a sectional view taken on line 7, 7 of Fig. 1. Fig. 8 is a sectional view taken substantially on line 8, 8 of Fig. 2. Fig. 9 is an enlarged view of one of the corners shown in Fig. 7. Fig. 10 is substantially a sectional view

taken on line 10, 10 of Fig. 1. Fig. 11 is an 55 enlarged sectional view of a portion of Fig. 8. Fig. 12 is also an enlarged view of the same. Fig. 13 is a top plan-view of a portion of the racks or crates arranged within the case. Fig. 14 is a sectional view, illustrating a simple method of securing the parts on the cross wires together. Fig. 15 is substantially a section taken on line 16, 16 of Fig. 13. Fig. 16 is a sectional view taken on line 17, 17 of Fig. 13. Fig. 17 is 65 a sectional view taken on line 18, 18 of Fig. 13, and Fig. 18 is a view in elevation of a portion of the end of the racks and supports therefor.

Referring to the drawings, in which my 70 invention is shown embodied in a box or case for containing bottles, as for example, beer bottles or the like, the box or case comprises suitable sides, ends, bottom and a top, which top may be omitted if desired. 75 The top is particularly intended for use where the cases are shipped, and it is desired to give the contents of the case as much protection as possible. I have not considered it necessary to illustrate the case knocked 80 down, or collapsed, for shipping or storage. The case comprises sides 1 and 2, ends 3 and 4, and a bottom 5, which parts may be made of wood, metal, or any equivalent, of the desired size and weight. I have illustrated 85 a case constructed of wood or similar material, which is preferably reinforced or strengthened, so as to give maximum strength for a minimum weight. The sides 1 and 2 are preferably reinforced at the top 90 and bottom by pieces 6, 6, etc., and the ends reinforced by pieces 7, 7, etc. The bottom 5 may also be similarly reinforced by the pieces or parts 11, 11, etc., preferably arranged upon the under side. Arranged on 95 the inner face of the sides 1 and 2 are strips or cleats 9, 9, and on the inner face of the ends, similar strips or cleats 10, 10, the same being suitably secured to the sides and ends in any desired manner. They are preferably 100 so arranged that they support the bottom the desired distance above the lower edges of the sides and ends. Reinforcing cleats 12 may also be arranged as shown. The cleats 11 may be of sufficient size to also support 105 the bottom. The sides and ends are provided with staples, wire eyes, or loops 15, 15, as most clearly shown in the enlarged

views Figs. 3 and 9. As shown the staples or loops have mating parts spaced from the adjacent sections and wires or retainers 16 are extended through the loops and bent over so as to be locked in position. Any equivalent for the loops 15, 15 and wire 16 may be employed, and the same may be made in the best form to produce the best results, but I have not considered it necessary to illustrate various equivalents or modifications. When the sides or ends are assembled and secured together, the bottom 5 being arranged as shown in Figs. 8 and 10, the bottom is supported and prevented from dropping out of the cleats 9 and 10. The cover or top 8 is preferably reinforced by strips or cleats 14, arranged at the sides, the cover being preferably of a width to extend flush with the outer pieces, with the cleats 6, 6 on the sides, as most clearly shown in Fig. 8. A simple construction for hinging the top to the body of the case, is illustrated in detail in Figs. 4 and 12, in which 24 are eyes secured to one part, as shown to the side or cleat 6, and 23 loops secured to the opposite part, as shown, the top, the two parts being secured together by wire loops 25, or their equivalent. This preferred construction allows the top to be folded back against the side when desired, so that it is out of the way, and the case takes up a minimum of room. It will be noted that the cover or top is cut out at 26, at the points where the same is hinged to the case. Any equivalent hinge construction may be employed.

A simple lock is illustrated in Figs. 1, 5 and 6, for securing the opposite or free edge of the cover and locking the same down. The lock shown comprises a wire 27, formed with a resilient loop 29, which is secured to the side 1 by staples 28, or their equivalents. The opposite end of the wire lock 27 is formed with an extended part 30 arranged to extend through an opening 33 in the top, and engages with the pin 32. The locking member 27 is preferably beveled or formed with an inclined part 31, so that the lock will automatically spring out of the way when the cover is forced down and back into position to lock the cover. The lock may be released by inserting a finger or suitable instrument through the opening 33, and pushing it out of engagement with the pin 32. Any equivalent lock may be employed, but the lock shown is practical, may be arranged inside of the case and is substantially flush with the inner face, and further, is simple and not likely to get out of order. In case of injury to it, or breakage, it may be easily replaced or interchanged with a new one.

Where the case is used for containing bottles, as for example, beer bottles, as mentioned, suitable means is arranged in the case for spacing and maintaining the bottles in position. For this purpose I have shown

a rack 18 and a rack 19, which are suitably secured in position in the case. The racks are preferably divided into cross partitions, the number of the same depending upon the size of the case and the number of bottles to be held. The racks shown are preferably arranged to be supported, are foldable, and are also arranged so as to maintain the bottom in position, if by chance the case is inverted.

As shown, the crates or racks are provided with an outside frame 17. The upper one is shown formed of cross wires 19 and the lower one of similar wires 18. A simple manner of connecting the wires by looping them at 34, where they cross, is illustrated in Fig. 14. It should be mentioned, however, that the wires may be twisted or secured together in any desired manner, and may be modified or changed as found desirable. They may be woven, twisted, welded, or constructed of punched material, and, in fact, they may be constructed in so many different ways and give similar results, that it is impossible to fully illustrate all of the modifications, and I have, therefore, not endeavored to show more than one construction. The lower crate or rack is supported by downwardly extending wires 21, which are preferably bent transversely as at 22, and rest upon the bottom 5, the ends 22 being long enough to engage into small holes in the sides or ends, or both. The upper crate or grate is supported from the lower one by links 20. It will be noted by referring to the detailed figures, Figs. 13 to 17, that the links 20 at the ends are bent around so as to pivotally secure the same to the ends of the frame 17. Links 20 along the sides are preferably bent to engage the cross wires 18 and 19, which wires are preferably formed as most clearly shown in Fig. 17, so as to prevent the loops becoming displaced. Referring to this figure, it will be noted that the wires 19 are bent at the end as at 36, and the wires 18 looped in substantially a similar way. This construction permits the racks to be folded together substantially as indicated in the dotted lines in Fig. 16, in which figure, however, the same is not shown completely folded. It will be noted that the supporting legs 21 having the extended lower ends 22, not only support the racks, but also prevent the same, as well as the bottom, from becoming accidentally removed from the case.

In setting up the case or assembling the same, three of the corners may be secured together, and then the same brought around to close the fourth corner, the bottom and partitions being positioned, and the fourth corner being locked in a manner depending upon the fastening employed. The top may be used or not, as preferred. The racks are positioned in the case, with the extending

feet 22 sprung into place in the holes in the walls. The case is then all assembled and ready for use. If the case is to be shipped by rail without contents, the case may be collapsed by undoing the fasteners, and the parts folded together, the racks being also folded so that a number of cases may occupy the space that would be required by one assembled case. When the cases are received 10 for filling and shipping, if any of the cases are damaged, as for example, one end is damaged, a new end may be readily provided and replace the damaged one, the parts all being interchangeable. If a number 15 of cases have different parts broken or damaged, the damaged parts may be replaced by or interchangeable with the good parts of other damaged cases, so that, perhaps, a considerable number of cases may be 20 repaired and only several be discarded or lost, where, if the cases could not be so repaired, all would be wasted. I have particularly mentioned the case as applicable for containing beer bottles. It may, however, 25 be employed for other uses wherever it may be found applicable. All of the parts of the box or case are interchangeable, including the ends, sides, bottom, cover, partitions, or crates, hinges, latching device, 30 etc., the construction permitting the easy setting up, interchanging, and knocking down of the box.

Having thus described my invention, it is 35 obvious that various immaterial modifications may be made in the same without departing from the spirit of my invention; hence I do not wish to be understood as limiting myself to the exact form, construction, arrangement and combination of parts herein 40 shown and described, or used mentioned.

Copies of this patent may be obtained for five cents each, by addressing the "Commissioner of Patents, Washington, D. C."

What I claim as new and desire to secure as Letters Patent is:—

1. A case of the kind described comprising side and end walls, means for detachably locking the same together at the corners, a bottom, means on the walls of the case for supporting the bottom, a spacing rack arranged within the case and provided with means engaging the walls of the case and the bottom and serving to maintain the rack and bottom in place.

2. A case of the kind described, comprising side and end walls, some of said walls being provided with recesses, means for detachably locking the walls together at the corners, a bottom, means on the walls of the case for supporting the bottom, a spacing rack arranged within the case and provided with portions engaging the bottom and the recesses in the walls of the case, and serving to maintain the rack and bottom in place.

3. A case of the kind described, comprising side and end walls, some of said walls being provided with recesses, means detachably locking said walls together at the corners, a bottom, means on the walls of the case for supporting the bottom, a spacing rack arranged within the case, said rack being provided with supporting legs resting upon the bottom and having lateral extensions engaging said recesses and maintaining the rack and bottom in place.

In testimony whereof, I have hereunto signed my name in the presence of two subscribing witnesses.

JOHN L. BUEHL.
